UNITED STATES PATENT OFFICE.

STANLEY W. LAWTON, OF NEW YORK, N. Y.

PHOTOPLAY ORCHESTRAL DIRECTOR.

Application filed July 31, 1923. Serial No. 654,830.

This invention relates to photoplay or-
chestral directors, and its main object is to
provide improved apparatus to enable an
orchestra and its conductor to furnish the
5 correct music to accompany the showing of a
motion picture without watching the screen.

Another object of the invention is the pro-
vision in connection with a plurality of
10 visual signals, some of which are visible
throughout a wide range, to the entire or-
chestra for example, and others of which are
visible throughout a restricted range, to the
conductor alone for instance, of apparatus
15 including a number of signal actuators each
capable of operating the various signals ac-
cording to a predetermined program.

Another object is to provide a movable
20 member adapted to carry a direction sheet
located in the range of vision of the con-
ductor for example, signals to attract the
attention of individuals or all the players
and means for illuminating the direction
25 sheet, the signals and illuminators being op-
erated in response to movement of the direc-
tion sheet carrier and signal actuators
thereon.

Another object is to provide an orchestral
director together with means for operating
30 the same in synchronism with a motion pic-
ture projecting machine and means for
changing the relative speed of the director
apparatus and the machine.

Another object is to provide an orchestral
35 director comprising a rotatable signal con-
trolling drum having more than one set or
group of signal actuators, and preferably
automatic means for associating one set or
group of actuators with the signals during
40 one revolution of the drum and a different
set during another revolution.

Still another object is to provide in con-
nection with a single orchestral director
whose operation is controlled by a motion
45 picture machine, simple means for discon-
necting the director from one machine and
placing it under the control of another, said
control changing means being operable by
mechanism within reach of an operator of
50 either of the projecting machines.

Fig. 1 is a diagram showing in end eleva-
tion a direction sheet carrier and signal op-
erator with its casing and associated signals
and operating circuits.

Fig. 2 is a front elevation of the carrier,
55 signals and casing shown in Fig. 1, certain
parts being broken away.

Fig. 3 is a detailed sectional perspective
of the signal operating cam switch assembly.

Fig. 3^a is a bottom plan view of the switch
cam shown in Fig. 3.

Fig. 4 is an enlarged perspective of a
switch shown in Fig. 1.

Fig. 5 is a front elevation of one mecha-
nism to be associated with a projecting ma-
chine to operate a signal controller in syn-
chronism therewith but at various relative
speeds.

Fig. 6 is a right hand end view of the
parts shown in Fig. 5.

Fig. 7 is a diagram of the local signalling
circuits, and

Fig. 8 is a development on a larger scale
of the surface of the direction sheet carry-
ing and signal operating drum.

The orchestral director is ordinarily lo-
cated in the orchestra pit directly in front
of the leader or director, while the project-
ing machines are located at a considerable
distance from the pit and screen. The sig-
nals are also located in the orchestra pit. I
therefore provide within the range of vision
of the conductor a movable member which is
adapted to carry a direction sheet and signal
actuators, together with local means for mov-
ing the direction sheet carrier. In the pro-
jecting machine room I provide mechanism
geared to the film to control the means for
moving the direction sheet and signal actu-
ators. When a motion picture is first run a
blank direction sheet is put on the carrier,
preferably a drum, and the machine set in
operation. The conductor watching the film
indicates the necessary directions as to ex-
pression, tempo, names and selections or any
other memoranda which will require the at-
tention of the conductor during the presenta-
tion of the film at a performance, and as he
marks the direction sheet he inserts signal
actuators which may conveniently be in the
form of pegs in a portion of the chart carry-
ing drum arranged to receive such actuators.

When a performance is to be given the drum
is again connected with the projecting ma-
chine and during the performance the pre-
determined signals will be given at the prop-
er time and the directions will be visible to
the conductor whose attention is attracted
to them by a special signal.

In Fig. 1 I have shown a drum 9 suitably
mounted for rotation on a horizontal axis 110
within a casing having a front wall 10, a rear
wall 11, a top 12 and a cover 13. The drum

carries a direction sheet 14 removably secured thereto and is provided, preferably at its opposite edges with one or more rows of holes 15, 16 adapted to receive signal actuating members such as pegs 17. Preferably I drive the drum by a step by step motion. As shown in Fig. 1 a magnet 18 actuates a lever carrying a pawl which advances a toothed ratchet 19 rotatably mounted on a suitable countershaft. The ratchet turns a pinion 20 mounted for rotation therewith, and the pinion meshing with a gear 20' on the drum shaft rotates the drum when magnet 18 is energized. In some cases it may be desirable to operate the drum with a continuous rather than an intermittent movement. The magnet or other drum rotating mechanism is controlled from one of the projecting machines 21 or 22 through mechanism within the auxiliary housing 23 of the machines which under control of the moving film intermittently completes an electrical circuit through the magnet 18, the source of power 24, conductor 25, movable contact 26 and fixed contact 27 of a switch to be described, thence through the circuit closer within housing 23, through fixed contact 28 and movable contact 29 of the switch, conductor 30, to the other end of the magnet coil. A local switch 31 may be conveniently mounted on a wall of the casing to disconnect magnet 18 from the projecting machine when desired.

With my improved apparatus the conductor making up the direction sheet has only one row of holes into which he may insert signal actuating pegs during a single revolution of the drum 9. For example, the right hand end of the drum may be arranged during the first revolution and the left hand end during the next revolution. This is quite an improvement over machinery in which the director has to choose from several rows of holes while the drum is operating and positively prevents errors arising through a selection of the wrong row such as may easily occur when a choice is necessary.

On the top 12 of the drum casing I provide an opaque housing 32 to hold a signal lamp 33 which is made visible to the conductor only through a front window 34. The top of housing 32 forms a convenient support for a lamp 35 arranged for unobstructed vision and thus to serve as a warning signal for the entire orchestra. A number of lenses 36 may be suitably supported around lamp 35 to direct light rays emanating from said lamp so as to prevent the lamp from annoying the spectators and to permit the use of a lower powered lamp to give an adequately visible signal to the orchestra.

To operate the signal lamps in accordance with the desired program I pivot two switch operating cams 37, 38 between a pair of ears

39 secured to the lower face of an insulating block 40 (Figs. 3 and 3^a). The block 40 is so positioned that the cams will be in peripheral alignment with each other and with the holes 15 at one end of the drum. Thus during the rotation of the drum, each peg 17 will first ride under and lift cam 37, and then will let cam 37 drop and lift cam 38. The cams actuate insulating pins 37^a, 38^a respectively to sequentially close pairs of contact springs 41, 41^a and 42, 42^a. The lower springs 41, 42 are mounted on the upper surface of the block 40, while the upper springs 41^a, 42^a are supported on a bus-bar 43 which is separated from the block 40 by a suitable insulating strip 44.

The switch block 40 is mounted for example on the inner surface of cover 13 near the top of drum 9 so that as a particular instruction passes into the position to be best viewed by the conductor, cam 37 will first be operated to flash the warning light 35. Cam 38 will later be actuated after an interval determined by the distance between the two cams and the speed of the drum to light the conductor's cue light 33 and to close the circuit, for any desired interval, depending on the length of the cam face of a direction sheet illuminating lamp 45. This lamp is suitably positioned within the casing to illuminate the written instructions which are to be next carried out.

The size of drum 9 is regulated by the length of a single program and the frequency of signalling intervals. It has been found that to provide sufficient room to display all the signals necessary for a performance of the usual length during one rotation of the direction sheet carrying drum requires altogether too big a drum and casing to be practical or useful in an orchestra pit where space is at a premium. I therefore arrange a drum of smaller diameter and divide its surface into two or more parts, each having space for a direction strip and a row of holes to receive signalling pegs. In order that the conductor may not be confused as to which section of the direction strip is to be followed, I provide as many individual lamps 45 as there are strips so that only one strip will be illuminated and thus rendered prominently visible at one time. By subdividing the drum longitudinally there are provided as many sets of holes and sections of direction strip as may be necessary to give the proper space for the directions. Means must therefore be provided to place the signals under the control of one set of signal actuators during one revolution of the drum and of a different set during another revolution of the drum. Where the drum is divided into not more than two parts this may be conveniently and automatically accomplished by placing an ordinary three way snap switch 46 hav-

ing an operating lever 47 in the path of nation. This arrangement avoids confusion movement of a pin 48 carried on one end of drum 9 (Fig. 1).

The operating circuits may then be arranged as illustrated in Fig. 7 in which the switch 46 is shown connecting stationary contacts 49 and 50 and breaking the connection between stationary contacts 51 and 52. With this circuit arrangement it is obvious that during the first revolution of the drum cams 37 and 38 at the right hand end of the drum are connected to the source of power 53 while cams 37' and 38' at the opposite end of the drum are disconnected from the source of power and will therefore have no effect on the signals. As each peg 17 is carried by drum 9 under cam 37 a circuit is completed from the negative pole of battery, contacts 49 and 50, springs 41^a, 41, 20 warning lamp 35 to the positive pole of battery. The lamp 35 is lighted in this circuit and warns the entire orchestra to be ready for instructions. The peg 17 next passes under cam 38 and completes parallel circuits from negative battery, contacts 49, 50, springs 42^a and 42 through the conductors cue light 33 and the lamp 45 which illuminates the right hand direction sheet. The conductor reads the directions and executes them, the surface of cam 38 being made sufficiently long to maintain the circuit through illuminating lamp 45 for the necessary time interval. At the end of the first revolution of the drum, pin 48 of drum 9 engages the three way switch operating lever 47 and throws the switch to its other position in which contacts 49 and 50 are disconnected and contacts 51 and 52 connected. Obviously the operation during the second revolution is the same as just described with the exception that it is the left hand end of drum 9 and cam switches 37' and 38' which control the operation of the signals and illuminating lamp 45' which illuminates only the left hand side of the direction sheet. When more than two direction sheets are carried on the drum counting relays may be substituted for the switch 46.

In order to render the instruction sheet visible through cover 13 I may make said cover entirely of transparent material, but preferably I provide at the proper place in said cover a transparent portion 54. To further aid in reading the directions I secure magnifying lenses 55 in position to magnify the portion of the direction sheet directly beneath them and which is to be read by the conductor at any given time. From the foregoing description it is seen that my machine consumes energy in the signaling circuits only when the signals are lighted, that the signals are lighted only at the instant they are needed and that only directions which are to be executed at once are made visible to the conductor by illumin-

ation. This arrangement avoids confusion and makes compliance with the directions the natural result since the presence of the machine is forgotten by the conductor except when it is necessary to attract his attention. 70

Referring now to the apparatus for controlling the operation of the signaling drum in synchronism with the movement of the film and which I have illustrated in detail in Figs. 5 and 6, 23 represents the housing 75 previously referred to which goes on the projecting machine and holds the apparatus for controlling the drum magnet 18. Since not all photoplays require the same length of time for presentation without repetition, 80 while projecting machines are run at a uniform speed, it is obvious that if the relative speed of the film and the signalling drum 9 is constant and sufficient space for direction sheets is provided on drum 9 to handle a 85 long program, a short program will not utilize all the available space on the surface of drum 9. I therefore provide a circuit controller which while operating the drum synchronously with the film nevertheless permits changes of the relative speed of these two elements. Thus when the program is short the drum may be run faster and the interval between successive movements of the drum may be made shorter 90 than is the case with a long program. 56 is a shaft in the projecting machine which is geared to the film and therefore operates synchronously with the film. I mount a gear 57 on shaft 56 for rotation therewith 100 and normally in mesh with a gear 58 carried by shaft 59 which also carries a worm 60. The worm meshes with a pinion 61 which turns a shaft 62 journaled in the casing 23. I mount a conducting rotor 63 on shaft 62, 105 and adjacent thereto on an insulating bar 64 I mount two slideable brushes 65 and 66 either or both of which may be clamped in any desired position as by the thumb nut 67. Brush 65 is arranged to continuously engage the cylindrical conducting surface of rotor 63 while brush 66 only makes contact with the projections 68 which are circumferentially disposed in different sections of the rotor. It is obvious that if brushes 65 110 and 66 are connected respectively to fixed contacts 27 and 28 of the switch previously described and shown in Fig. 1, each revolution of rotor 63 will complete the operating circuit for magnet 18 as many times as there are projections 68 in the path of brush 66. In the present instance I have shown 4 sets of projections 68, one set consisting of a single projection, another of two diametrically opposed projections, another of three 120 spaced 120° apart and the set with which brush 66 is shown cooperating spaced a quarter of a revolution apart. This latter position of brush 66 is that which would be used for the short programs and the short- 130

est interval between successive steps of signalling drum 9. As the program becomes longer brush 66 may be moved to the right so as to slow down the operation of the signalling drum 9 as necessary. Obviously as many sets of projections with as many projections in each set as desired may be provided in any particular case on the drum 63.

10 In high class motion picture theatres it is customary to employ at least two projection machines so as to permit the presentation of programs uninterrupted by removal and replacement of a reel of film. In order 15 that my orchestra director may be used in such houses without interruption, I have provided a switch which may be located preferably on the ceiling of the projection room and which may be easily operated 20 from a distance to connect the directing apparatus with whichever machine is in use at the time. In the form shown I employ a simple double pole double throw switch having segmentally shaped movable contacts 26 25 and 29 and two pairs of fixed contacts 27, 28 and 27', 28'. The movable contacts are connected by an insulating cross bar to which is secured a cord 69 which passes over pulleys 70, 70' located just over the projecting machines 21 and 22 (Fig. 1). The ends of cord 69 terminate in suitable handles 71, 71' which are conveniently located within the operators reach. Thus when the operator shuts down one machine and starts the 30 other he need only pull the handle 71' on the machine which he is starting in order to throw the switch from one extreme position to the other and so connect the circuits for magnet 18 to the rotor on the projecting machine which is in operation.

40 In Fig. 8 I have shown about half size a development of part of the surface of the drum 9 carrying a director sheet 14 divided into two sections each of which has an adjacent row of holes 15 to receive signal actuating pegs 17. The time from the beginning of the performance may be marked in any suitable units such as minutes either on the margin of the drum or as shown in the 45 drawing it may be printed in advance at a convenient place such as the center of the direction sheet.

50 While I have shown but one embodiment of my invention it is obvious that it is susceptible of various forms and that many changes may be made in the details of construction without in any case departing from the spirit of the invention as defined by the claims. For example, the signalling 55 drum may be divided into more than two parts, in which case additional sets of cam parts, actuating pegs, direction sheet switches, illuminating lamps and direction sheets would be provided. Moreover by a suitable switch 60 the orchestral director may be associated

with any one of a number of projecting machines. Obviously the space on the direction sheet is limited only by considerations of the size of the complete drum which may vary within wide limits.

70 It should also be noted that the circuit controlling rotor need not be of conducting material, as brushes 65 and 66 might be arranged in tandem, normally out of contact, while each projection 68 would make contact between the brushes in passing them and would thus be a contact maker within the intention of the claims.

75 When the drum 9 is made of non-metallic material such as wood, I may surface the 80 portions of the periphery which are to be provided with holes 15, 16, adapted to receive signal actuating members 17 with light metal strips, such as aluminum, thereby facilitating drilling of the holes and lengthening the life of the drum.

85 A number of improvements are claimed in my applications as follows: 30,973 filed May 18, 1925, and 107,049, 107,050 and 107,051 filed May 6, 1926.

90

I claim:

1. In a photoplay orchestral director the combination with a signal visible throughout a wide range, a signal visible throughout a restricted range, a signal to illuminate an 95 instruction sheet, and signal energizing circuits, of a rotatable drum adapted to carry such a sheet, and projecting members in peripheral alignment thereon and near one edge of the sheet, an energizing circuit for 100 said wide range signal, a pivoted cam and responsive to passage thereunder of one of said projecting members, a switch controlled by said pivoted cam to flash said wide range signal, and a second pivoted cam and controlling means operated thereby for said restricted range signal and said illuminating signal, said second cam being in peripheral alignment with said first cam whereby rotation of said drum and projecting members 110 will operate said cams sequentially and means for rotating said drum.

105 2. In a photoplay orchestral director the combination with a signal light, an instruction illuminating light, a rotatable drum 115 adapted to carry an instruction sheet to be illuminated by said light and having removable pegs on its periphery, of a switch comprising a pair of contact springs mounted one above the other on an insulating block, 120 a second pair of springs on said block, two cams positioned to ride over said pegs and thereby sequentially close said pairs of contact springs, circuits for said light extending respectively through said contact springs 125 and means for rotating said drum whereby said signal light will be flashed and said illuminating light will illuminate said instruction sheet for a definite interval each time a peg passes under said cam.

130

3. In a photoplay orchestral director the combination with a casing having walls and a cover including a transparent portion, a signal lamp mounted outside the casing for unobstructed vision throughout a wide range, and a lamp mounted within the casing, of a rotatable drum mounted within the casing having a director chart and adapted to be viewed through said transparent cover, said casing lamp being arranged to illuminate such visible portion of the drum, and means carried by the drum for actuating said wide range signal light and said lamp according to a predetermined program.
- 5 4. A photoplay orchestral director drum having signal actuating pins on opposite edges thereof, and a direction strip mounted on said drum between said pins and having two columns of direction symbols corresponding to the pins adjacent thereto.
- 10 5. A direction strip for a photoplay orchestral director having two columns of direction symbols with spaced indicating marks indicating regular intervals of time.
- 15 6. A photoplay orchestral director comprising a cabinet, a signal actuating drum mounted therein, a direction strip carried by said drum, an external warning signal lamp, an internal reading lamp arranged adjacent said direction strip, and signalling means actuated by said drum for illuminating said warning lamp and said reading lamp sequentially as the drum rotates.

STANLEY W. LAWTON.
